Primary Examiner — Catherine Tuttle*(74) Attorney, Agent, or Firm* — McCracken & Frank LLP**CLAIM**

The ornamental design for an overcap, as shown and described.

DESCRIPTION

FIG. 1 is an isometric view of the front, top and right side of the overcap showing our new design;

FIG. 2 is a front elevational view of the overcap of FIG. 1; FIG. 3 is a rear elevational view of the overcap of FIG. 1; FIG. 4 is a right side elevational view of the overcap of FIG. 1;

FIG. 5 is a left side elevational view of the overcap of FIG. 1; FIG. 6 is a top plan view of the overcap of FIG. 1; and, FIG. 7 is a bottom plan view of the overcap of FIG. 1.

The broken lines are included for the purpose of illustrating environmental structure that forms no part of the claimed design.
